U.S. Cl. D87—1 R

FIG. 1

FIG. 2

FIG. 3

FIG. 4

FIG. 5

FIG. 6

FIG. 1 is a top front perspective view of a carrying case showing my new design;

FIG. 2 is a top rear perspective view showing the side opposite that seen in FIG. 1;

FIG. 3 is a top plan view;

FIG. 4 is a side elevational view;

FIG. 5 is a front elevational view;

FIG. 6 is a rear elevational view; and

FIG. 7 is a view similar to FIG. 1 but with the cover in a raised position.

The bottom is substantially plain and unornamented. The broken lines in FIGS. 1, 2 and 3 represent a fold line, the folding portion being illustrated in FIG. 7 in the open position.

I claim:

The ornamental design for a carrying case, as shown and described.
